Philip M. Nawn

FIG. 2.

BY:

Paul J. Darrow.

ATTORNEY.

UNITED STATES PATENT OFFICE.

ERNEST A. ANHEUSER, OF MILWAUKEE, WISCONSIN.

FILE-MILLING HEAD.

Application filed January 6, 1927. Serial No. 159,305.

This invention relates to rasps and files, and the cutting of steel blanks that, after hardening, form those implements used as abrasive elements on metals or other substances requiring a certain finish performed with tools of this class.

The objects of the invention provide a preferred abrasive, or scored surface that forms the "tooth" consideration of files and the like. The obtaining of a convex surface coincident with the cutting of the scores or teeth. The eliminating of a consequent treatment of the milled bars whereby a sand-blasting application irregularly lessens an unavoidable concavity left in the toothed surfaces of files after cutting same by methods heretofore common. The minimizing of the work of cutting tools that score the blanks prior to heat-treating and coincidentally increasing the production of finished product. The providing of a reciprocating assembly which permits of a departure in the inclined relation between the forming mechanism and the blank; and the provision whereby a cutting path is maintained along the arc of a limited circle without disturbing the blank's surface at the opposite arc's path notwithstanding the condition wherein both arcs are bisected by the said blank's longitudinally medial line.

Other objects will be seen in the drawing, described in the specification, and pointed out in the appended claims, all of which form part of this application.

Referring to the drawing:

Fig. 1 is a sectional elevation taken on line 1—1 of Fig. 2.

Fig. 2 is a plan view taken on line 2—2 of Fig. 1.

Fig. 3 is a development diagram of the cutting cycle.

Fig. 4 is an enlarged fragmentary detail of a cut blank.

Fig. 5 is a section on line 5—5 of Fig. 4.

Similar characters of reference apply to like parts throughout the several views. The said views are intentionally simplified and somewhat diagrammatic in omitting the actual structural machine conditions, which may be varied in design for acquiring a working and economically produced assembly. The improvement is intended as an adjunct attachable to any standard make of milling-machine, or drill-press, where is present the necessary rotative action accompanied with the power common to machines

of this class. The device may also be operated in a horizontal, as well as the vertical position here shown.

The blank stock is understood to be in that physical state where cutting tools are used to shape the metal. The finished product being later subjected to a heat-treating process that leaves same a hardened element not easily affected by other than a grinding process, which includes where same is requisite for cleaning, the commonly adapted sand-blast operation, for polishing and eliminating any unevenness resulting from either the cutting or the hardening stages of manufacture.

Referring to the drawings, and particularly the Figs. 1 and 2, the improvement is shown as adapted to existing machines having a table 1, here made adjustable for raising and lowering through means of a screw 2 that is threaded to coincide with a nut-like enlargement 3 of a machine frame-work. The blank B, of steel-strap stock, is fed across the table in intermittent steps that occur in synchronism with a selected period of the machine's rotating shaft S. This intermittent progress of the blank B is not accounted for here, because of the numerous ways adaptable, all of which require some connection to a portion of the mechanical assembly beyond the present consideration.

A supporting unit 4 is suitably arranged to span the table 1 and the blank B through having its base recessed at R for allowing the said table to be adjusted independently of the unit aforesaid, and to also permit the passage therethrough of the intermittently advanced ribbon of stock, which is in a measure, a continuously cut blank that is afterwards severed into specified lengths that form the intended tools. A rotary head H is formed of segmental blocks 6 which are grouped to arrange themselves about the end of the vertical shaft S. Each segment 6 is independently slidable vertically and all rotate with the shaft S by virtue of being splined, or keyed to the aforesaid shaft as indicated by S'. The vertically free segment blocks are provided with peripheral projections 7 which rotate in a horizontally arranged annular cam track 8 formed in the supporting unit 4. The several segments 6 are machined to function as chucks that receive a complement of cutting bits 9 whose effective points

9' project below the bottom faces of their respective segment. The cutting field of the points 9' are confined to a fixed horizontal plane, and their effect upon the worked stock is determined by the adjustable means 5 1, 2 and 3 mentioned above. The assembled head H offers a plunger-like element that is rotative with the shaft S, and vertically reciprocative in the large bore M of the 10 unit 4.

The serrations, or teeth T, of the scored blank, are arranged to form parallel arcs of a circle whose center is identical with the shaft's vertical center, and whose arc- 15 bisecting radius is coincident with the longitudinal center-line of the aforesaid blank, as shown in Fig. 4. The formation of arcuate edges on the blank is performed at the feed end, in this instance, because of the 20 shaft's revolutionary direction, and, in order to allow this, the remaining segments 6, not in this cutting zone, must be raised up, or, in process of being raised, so that the opposite circular zone, traversed by the blank, will 25 be open and free of the cutting bits whose points would otherwise ruin the work already performed. In order to provide this condition, the cam-track 8 is contoured to 30 present its lowest position, at the cutting zone (a) from which zone it raises and again lowers to leave the said track at its highest elevation over the opposite zone (b). The inclination of the cam-track 8 is determined to be such that the worked stock is only 35 affected at the zone (a). This elevating of the segments 6 offers a certain space between the blank and the elevated cutters and this said space is utilized to permit the table of being noticeably inclined as shown. This 40 inclination provides a cutting path for the points 9' that is convex over the blank B instead of concave as is the case in tools cut by heretofore employed processes. The 45 concave result is objectionable, and the product of this concave method of cutting teeth, must be subjected to an unreliable and irregular operation for remedying this defect, wherein sand-blasting is employed in an endeavor to level the edge-adjacent areas 50 down to an approximation of the center of a cut blank. This offers a very indefinite result in a condition where 2 or 3 thousandths are noticeable volumes in the work upon which these tools, or files are used, such as: 55 auto-bodies, sheet-metal fixtures, containers, etc., where the slightest departure from a smooth surface becomes magnified when the finishing polish is applied.

The cutters 9 are arranged in step-like 60 order so that one revolution of the head H will cut a complete tooth. The blank is automatically advanced across the inclinedly fixed, but vertically adjustable table 1 as per feathered arrow, in definite steps 65 that are equivalent to the "pitch" of the

arcuately parallel teeth, and, on this account, a gap is left in the cutting circle by leaving out bits to permit the blank to be intermittently forwarded across the said table. The blank may also be reversed and worked 70 similarly to provide a double edge tool if desired; this is indicated in Figs. 4 and 5.

The views are purposely diagrammatic in the sense of assembling the parts; however, this phase has been cared for; and the 75 separate portions, not particularly defined here, for allowing the unitary head, as here disclosed, to function with its supporting means, have been developed to a point of unquestioned feasibility.

Having described the invention, what is claimed and desired to protect by Letters Patent, is:—

1. A rotary milling head having, circularly arranged bits grouped into sets upon 85 the bottom face of a rotating head, a work-supporting table said head divided to offer a plurality of segments independent of each other and independently reciprocative in operation for approaching or receding 90 from the aforesaid table.

2. A rotary milling head having, circularly arranged bits grouped in segmentary sets in operatively reciprocative segments of 95 said head, said sets containing a graduated complement of bits that project below the bottom face of the aforesaid segments to partially cut arcuately formed teeth in a blank disposed upon a support, said support being upwardly inclined from the feed end. 100

3. A rotary milling head having, a stationary unit, cutting bits, bit holding quadrants, a revolving shaft, said bits arranged about the vertically revolving shaft, each quadrant slidably keyed to the shaft aforesaid for independent reciprocative action upon the shaft aforesaid.

4. A rotary milling head having, a central revolving shaft, a cutter head, said shaft slotted to permit the cutter head assembly 110 comprising segmentary quadrants to reciprocate thereon while horizontally rotating as a unit.

5. A rotary milling device having, a revolving head assembly provided with cutting bits, a stationary unit bored to envelope the said assembly, projections on said assembly's periphery, an annular cam track around the unit's bore to receive the several projections aforesaid, the contour of the cam 115 track being varied continuously to offer one portion disposed in a horizontal plane that lies beneath the plane of the remainder of said track.

6. A rotary milling head having, a rotative assembly, a sleeve member for centering the plurality of quadrants forming said rotative assembly, an adjustable table horizontally inclined and symmetrically aligned with and below said member, and means to 125 130

allow vertical adjustment of the table aforesaid.

7. A rotary milling head comprising, a stationary unit, a rotative shaft, segmentary quadrants carrying cutting bits assembled about and reciprocative upon said shaft, an annular cam path fashioned in the unit aforesaid, projections integral with the several quadrants extending into said path, 5 said path designed to offer a contour that induces the reciprocative action in the rotating segmentary quadrants aforesaid.
8. A rotary milling device having, a rotative assembly comprising segmentary quadrants equipped with cutting bits surrounding a shaft, a stationary unit bored to center said assembly, a table member adjustable beneath said unit, a recess formed across the base of said unit wherein the aforesaid table may approach or recede from the aforesaid 15 rotative assembly.

In testimony of which I hereto affix my signature.

ERNEST A. ANHEUSER.
